UNITED STATES PATENT OFFICE.

ROBERT HUNTINGTON, OF MEDFORD, MASSACHUSETTS.

APPARATUS FOR LAUNCHING LIFE-BOATS.

1,202,526.

Specification of Letters Patent.

Patented Oct. 24, 1916.

Application filed October 19, 1912. Serial No. 726,718.

To all whom it may concern:

Be it known that I, ROBERT HUNTINGTON, a citizen of the United States, residing at Medford, county of Middlesex, State of Massachusetts, and whose post-office address is No. 150 State street, Boston, Massachusetts, have invented an Improvement in Apparatus for Launching Life-Boats, of which the following description, in connection with the accompanying drawing, is a specification, like characters on the drawing representing like parts.

This invention relates to apparatus for launching life boats from the deck of a vessel, and has for one of its objects to provide a novel device of this nature by which the life boats may be lowered equally well from either side of the vessel and also to provide a novel device by which the various life boats can be lowered one after the other successively without the necessity of raising a tackle and falls each time that a boat has been cast off.

Life boats are now almost universally lowered by means of davits and falls and tackle suspended therefrom. The boat to be lowered is hooked onto the tackles and then the ropes of the two falls, one at each end of the boat, are paid out to lower the boat. In order to lower a second boat it is necessary to draw in the rope of the fall to bring the tackles back up to the deck again, and this stop in the operation is almost always a source of delay because of the fact that when the tackle is disconnected from the lowered boat the ropes of the falls will almost invariably twist, thus necessitating the untangling of the ropes before the tackle can be elevated.

With my improvements a boat can be lowered and cast off and then another boat can be immediately connected to the lowering apparatus without the necessitating of elevating a tackle block or other connecting device. I accomplish this object by employing an endless chain arrangement for lowering the boats which is so constructed that the boats can be connected thereto at any point. I have also provided a novel manner of storing and handling the boats on the deck of the vessel so as to permit them to be launched from either side of the vessel with equal facility.

Referring now to the drawings wherein I

have illustrated a preferred embodiment of my invention, Figure 1 is an end view of the vessel showing the arrangement and operation of my boat-handling apparatus; Fig. 2 is a plan view showing the way the boats will be stored on the deck of the vessel; Fig. 3 is an enlarged view of the davit and lowering apparatus; Fig. 4 is a side view of the apparatus for handling one of the boats; Fig. 5 is a view similar to Fig. 3 showing the davits swung out-board and with a boat ready to be lowered; Fig. 6 is a diagram view showing the way in which the trolley rope 26 is connected.

1 designates a vessel having a deck 2 on which the life boats 3 are stored, said boats being sustained by boat-supporting cradles 100. In this invention the life boats are lowered through the medium of an endless chain fall 4 which is suspended from davits 5 that are pivoted to the deck of a vessel. A pair of davits and endless chain falls are required for lowering each boat, but as the two davits and their falls are the same, a description of one will suffice for both.

Each davit is pivoted to the deck of the vessel at 7 and is shown as provided at its upper end with a laterally-extending portion 8 which sustains two direction pulleys 10 over which the endless chain fall 4 passes. Each davit also sustains a sheave or pulley 9 situated to rotate about an axis at right angles to that of the pulleys 10. The endless chain fall 4 passes up over the pulleys 10, thence down around a controlling sprocket wheel 11, thence up over the pulley 9 or sheave 9, and thence down the side of the vessel to the water, and thence back to the pulley 10 again, thereby making an endless fall with a loop extending from the davits to the water. The controlling sprocket 11 may be mounted in any suitable place, either on the deck or on the davit, and means are associated therewith for controlling the lowering movement of the fall. In the embodiment of the invention herein shown this controlling sprocket is carried by the davit 5 and is fast on a shaft 12 journaled in suitable bearings formed in the davit and having rigid thereon a gear 13 which meshes with a pinion 14 that in turn is rigid with a friction drum 15 sustained by the davit.

16 is a strap brake which encircles the brake drum 15, one end of said strap being

connected to the davit at 17, and the other end being connected to an operating lever 18 pivoted at 200 to the davit and by which the braking pressure of the strap brake can be applied. The lever 18 is shown as having a cord 19 connected thereto which is adapted to be secured to a cleat 20 formed on the davit thereby to hold the brake in operation.

10 The boats 3 are provided at each end with hooks 21 adapted to hook into any one of the links of the chain 4. In lowering a boat it is carried to the side of the vessel 1 and the hooks 21 of the boat are hooked into the links of the endless chain falls 4, as shown in Fig. 3. The davits are then swung outwardly into the position shown in Figs. 1 and 5, thus carrying the suspended boat 3 beyond the side of the vessel. The boat 20 can be loaded either when it is in the position shown in Fig. 3 or when in the position shown in Fig. 5, and during this operation the brake bands 16 are firmly applied, thus locking the sprocket wheels 11 from movement and holding the falls 4 perfectly stationary. When the boat is loaded and it is desired to lower it, the braking pressure of the brake bands 16 is eased up, and as the weight in the boat 3 is sustained entirely by one run of each of the falls, said run of each fall will be paid out and the other run will be taken up, as will be obvious. By manipulating the brakes 16 the speed at which the boat is lowered can be regulated to a nicety so that the boats may be quickly lowered without danger to its occupants.

When any boat 3 has reached the water it can be readily disconnected from the falls and the falls are then immediately ready for the lowering of another boat because the boats 3 can be hooked onto the falls at any point. One boat after another can, therefore, be rapidly lowered without the necessity of taking time to return the tackle from the lowered boat to the deck of the vessel by winding up or drawing in the rope. I consider this endless chain fall construction as a very important feature of my invention.

50 From the above description it will be noted that in launching any boat the davits 5 are swung from their in-board position shown in Fig. 3 to their out-board position shown in Fig. 5. I have provided herein a simple mechanism for giving the davits their swinging motion, which mechanism is so constructed that both davits are swung simultaneously. The mechanism herein shown comprises a segmental rack 32 fixed to the floor of the deck at the foot of each davit and a pinion 33 journaled to the davit and meshing with the rack, so that by turning the pinion the davit will be swung forwardly or backwardly. For operating the davits simultaneously, I provide a gearing

mechanism connecting the two pinions 33. As herein shown each pinion is fast on a shaft 34 journaled in the davit which has fast thereon a bevel gear 35 that meshes with another bevel gear 36 fast on a shaft 37 also 70 journaled in the davit. Each shaft 37 has a bevel gear 38 thereon on its lower end which meshes with a bevel gear 39 fast on a shaft 40 that extends from one davit to another and preferably constitutes the pivot 75 on which the davits turn. The shaft 40 is journaled in suitable bearings 41 secured to the deck 2. One or both of the shafts 34 may be provided with a crank 42 so that by turning either crank both pinions 33 will 80 be operated thereby swinging the davits forwardly or backwardly.

420 designates a stop associated with the segmental gear 32 for limiting the inward swinging movement of the davit and the 85 outward movement is limited by a stay member 43 in the form of a cord which is connected to one end of the davit and is anchored at the other end to the deck of the vessel.

90 In order to permit the boats to be lowered with equal facility from either side of the deck of the vessel, I propose to store the boats in a line extending across the deck of the vessel, as shown in Fig. 2. I also propose to employ a boat-transferring device which will now be described for taking the boats one at a time from their resting place and delivering them to the lowering device. This boat-transferring device consists of two 100 rails 22 extending across the deck of the vessel above the boats 3. Mounted on each rail is a carrier 23 provided with a block and tackle suspension device 24 adapted to hook into a hook 25 on the boat. The carriers 23 are each trolleyed back and forth on the tracks or rails 22 by means of a trolley rope 26. I have provided a trolley rope rigging which is easily operated and which is so constructed that there is never any slack 110 therein which can become twisted up. As herein shown, the carrier 23 has connected to each side thereof a pulley block 27, 28, and each rail 22 has at each end thereof a double pulley block, said pulley blocks being designated 29 and 30, respectively. One end of the rope 26 is connected to the pulley block 27, and said rope passes thence around one of the pulleys in the pulley block 30, thence around the pulley and the pulley 115 block 27, thence around the other pulley in the pulley block 30, thence the entire length of the rail 22 and around one of the pulleys in the pulley block 29, thence around the pulley and the pulley block 28, thence 120 around the other pulley in the pulley block 29, and thence to the pulley block 28 to which it is permanently secured. By means of this rigging each of the carriers 23 can be moved longitudinally of its track 22 by 125 130

simply drawing one way or another on the strand 31 of the rope 26 which extends the full length of the track.

In operating the device and assuming that 5 the davits are in the position shown in Fig. 3 the carriers 23 will be operated to take the first boat 3 and transport it laterally into position to be hooked onto the falls 4. After 10 the boat is secured to the falls and has been detached from the carrier, then the 15 crank 42 is operated to turn the pinions 33 thereby swinging the davits into the position shown in Figs. 1 and 5, thus carrying the boat outside of the vessel. During this 20 time the brakes 16 are firmly set so as to lock the falls against movement. The boat may then be loaded, and when it has been loaded the brakes are released sufficiently to allow the loaded boat to be lowered by 25 its own weight. While the first boat is being lowered the carriers 23 may be operated to bring another boat into position to be connected to the endless chain falls, and as soon as the first boat has been lowered and cast 30 off the davits are returned to the inboard position shown in Fig. 3, the brakes are set and the second boat is immediately hooked onto the endless chain falls. The davits are then swung outwardly into the outboard position shown in Fig. 5, the second boat is 35 loaded and then lowered as above described. This operation of filling and lowering the boats can be accomplished quickly and without any loss of time because there is nothing 40 about the rigging which can become tangled and because no time need be lost in returning a tackle from a lowered boat back up to the deck of the vessel before a second boat can be lowered.

45 I propose to have a boat-lowering device such as above described at each side of the vessel 1 at each end of the track 22 so that if desired boats can be lowered from either side of the vessel. By means of my improved boat-transferring device the boats 50 3 can readily be delivered at either side of the vessel 1, and, therefore, all the boats can be lowered from that side of the vessel at which the conditions are most favorable. Further, if desired the davits on both sides 55 of the vessel might be used simultaneously.

60 I have used herein the term "endless chain" as referring to the falls, but it is not necessary that these falls should be in the form of chains composed of links, as they might be any suitable flexible member, such as a rope or cable provided it had provision for attaching the boats 3 thereto at a series of points along its length. A chain composed of links is a convenient form of endless fall, but my invention is not limited to the use of a chain. I have used the words "endless chain" as a convenient expression for describing the endless fall.

65 Upon referring to Fig. 2 it will be seen

that the distance between the tracks 22 is greater than the boats 3. The advantage of this construction is that if an accident occurs and the vessel 1 sinks before all the boats can be lowered, those boats which have 70 not been lowered can be unslashed and will float as the vessel 1 sinks, and as the vessel sinks they will float up between the tracks and will not be caught by the tracks as would be the case if the tracks were nearer together. 75

Having fully described my invention, what I claim as new and desire to secure by Letters Patent is:—

1. In a boat-launching device, the combination with a vessel, of two davits mounted to swing over the side of the vessel, means connecting said davits by which they may be simultaneously operated from a single point, and endless boat-lowering members 80 85 sustained by the davits.

2. In a device of the class described the combination with a vessel of two davits each presenting a forked lower end which is hinged to the vessel, a segmental gear fixed 90 to the deck of the vessel and situated between the arms of the fork of each davit, a gear journaled in the fork end of each davit and meshing with its segmental gear, means connecting said gears whereby both may be 95 rotated in unison from a single point, thereby to swing both davits simultaneously in-board and out-board, and endless chain falls sustained by the davits.

3. In a device of the class described, the combination with a vessel, of a davit presenting a forked lower end which is hinged to the vessel, a segmental gear fixed to the deck of the vessel and situated between the branches of the forked end, a gear journaled 100 in said forked end and meshing with the fixed segmental gear, means carried by the davit for operating said gear whereby the davit may be swung inboard or outboard, 105 and endless chain falls sustained by the davit 110 and by which the boat may be lowered.

4. In a device of the class described, the combination with two davits, each having a forked lower end, of a segmental gear for each davit fixed to the deck of the vessel 115 and situated between the arms of the fork thereof, a shaft extending from one davit to the other and on which both davits are pivotally mounted, a gear carried by each davit meshing with its segmental gear, connections between each gear and said shaft whereby the gears may be operated in unison to swing both davits simultaneously in-board or outboard. 120

5. In a device of the class described, the combination with two davits, each having a forked lower end, of a segmental gear for each davit fixed to the deck of the vessel and situated between the arms of the fork thereof, a shaft extending from one davit to 125 130

the other and on which both davits are pivotally mounted, a gear carried by each davit meshing with its segmental gear, connections between each gear and said shaft whereby the gears may be operated in unison to swing both davits simultaneously inboard or outboard, and endless-chain falls carried by both davits.

In testimony whereof, I have signed my name to this specification, in the presence 10 of two subscribing witnesses.

ROBERT HUNTINGTON.
